DESIGN FOR AN ASPIRATING AIR DIFFUSER

George C. Lewis, Bryn Mawr, Pa.

Application February 18, 1939, Serial No. 83,091

Term of patent 14 years

To all whom it may concern:

Be it known that I, George C. Lewis, a citizen of the United States of America, residing at Bryn Mawr, in the county of Montgomery and State of Pennsylvania, have invented a new, original, and ornamental Design for an Aspirating Air Diffuser, of which the following is a specification, reference being had to the accompanying drawing, forming part thereof, in which:

Fig. 1 is a side elevation of an aspirating air diffuser, showing my new design.

Fig. 2 is a bottom plan view of Fig. 1.

Fig. 3 is a section on line 3—3 of Fig. 1.

I claim:

The ornamental design for an aspirating air diffuser, as shown.

GEORGE C. LEWIS.
